(57) **CLAIM**

The ornamental design for a portable device gaming dock, as shown and described.

DESCRIPTION

FIG. 1 is a front perspective view of a portable device gaming device showing our new design;

FIG. 2 is a rear perspective view thereof;

FIG. 3 is a top plan view thereof;

FIG. 4 is a front elevational view thereof;

FIG. 5 is a bottom plan view thereof;

FIG. 6 is a left side elevational view thereof;

FIG. 7 is a right side elevational view thereof; and,

FIG. 8 is a rear elevational view thereof.

The broken lines, which define the bounds of the claimed design, form no part thereof. The portions shown in broken lines are for illustrative purpose only and form no part of the claimed design.
